COIN CONTROLLED METER

Samuel Lee Miller, Maywood, Ill.

Application June 10, 1936, Serial No. 84,533
In Great Britain February 25, 1935

14 Claims. (Cl. 194—74)

This invention relates to coin-actuated time-controlled devices for dispensing various things or services which can be rented at a fixed rate per time unit, for instance per day or per week. 5 Such devices are particularly intended for services employing electric current, for instance, radio broadcast service, telephone service and the like, in which case an electric switch or electric switches may be operated by the device by the insertion 10 of one or more coins of predetermined sizes and values.

An object of the present invention is to provide a device of the character described employing a 15 clock mechanism which is self-contained so that the user cannot stop it or tamper with its operation.

Another object is to provide a device of the character described which has the greatest possible flexibility in the number and combination 20 of coins to be used, and of the elements, such as operating levers, electric switches and the like to be actuated thereby, as well as in the number and combinations of circuits to be closed by such switches.

25 With a view to attaining these objects the present invention provides a coin-actuated time-controlled device comprising a clock mechanism, a coin-retaining member movable to an operative and an inoperative position under control of the 30 clock mechanism, and an element adapted to be held in an operative position by a coin supported by the retaining member when the latter is in operative position and to be released when the retaining member is in its inoperative position.

35 This device is adapted for the sale or lease of various apparatus giving services which are vendable on a time basis, and particularly apparatus employing electric current such as radio receivers, television sets, refrigerators, electric signs and 40 the like.

One embodiment of the present invention, comprising a multiple coin, multiple switch arrangement is illustrated, by way of example, in the accompanying drawings, in which:—

45 Fig. 1 is a front elevation of the housing of the device;

Fig. 2 is an enlarged elevation on the line 2 of Fig. 3;

50 Fig. 3 is an enlarged vertical section on the broken line 3—3 of Fig. 1;

Fig. 4 is a similar section viewed on the line 3—3 but looking in the opposite direction;

55 Fig. 5 is a horizontal section on the broken line 5—5 of Fig. 4;

Fig. 6 is the same as Fig. 5 but showing the parts in a different position;

Fig. 7 is a detail of the electric switch of Fig. 3;

Fig. 8 is a partial front elevation of the device with the front removed, as viewed on line 8—5 of Fig. 5, showing the clock mechanism and parts controlled thereby;

Fig. 9 is a similar view on the line 8 of Fig. 5 with the clock mechanism removed showing the slot closing bar, the coin retaining bar, and the 10 key controlled lever;

Fig. 10 is a similar view on the line 10 of Fig. 5 showing the slot closing bar, the coin retaining bar, and the clock controlled lever;

Fig. 11 is a partial enlarged sectional view on 15 the line 11 of Fig. 1;

Figs. 12 to 15 inclusive are partial vertical sectional views similar to Fig. 4 showing the coin slot and illustrating the path of the coin there-through; and

20

Fig. 16 is a diagram of electric connections.

The device illustrated comprises a meter having a hollow housing 20 open at the back and adapted to be closed by a cover 21 which is secured therein in any desired manner, as by bolting the housing 25 against a flat surface which retains the cover in place so that access cannot readily be had to the parts enclosed within the housing. Within the bottom of the housing is located a coin box 22 which has a series of coin openings 22^a in the 30 top, and which is closed at the rear but is open toward the front of the housing 20, which housing has an opening 23 immediately in front of the coin box which is closed by a cover 24 retained by means of a lock 25. A sheet 26 is preferably carried by the cover and has instructions printed thereon for the operation of the meter.

35 A series of four coin slots 27 (Fig. 1) numbered 1, 2, 3 and 4 from left to right, are provided in the front of the housing for the insertion of coins, 40 as will later be described in more detail. Back of these coin slots and between them lies a series of one or more switch blocks 28 which rest upon the top of the coin box 22, each of which has a rib 28^a adapted to engage any one of grooves 45 29 in the top of the coin box in order to position the switch block with respect to the front of the housing to accommodate coins of different diameters, as will later be explained.

At the same time a rib 28^b on the bottom of 50 each switch block engages one of the grooves 30 in the top of the coin box. Similar ribs 28^c and 28^d in the top of the switch block engages a series of grooves 31 and 32, respectively. The 55 grooves 31 and 32 are contained in a wedge plate

33. Each switch block is positioned in the desired groove in the top of the coin box and in the corresponding grooves in the wedge plate, and the whole is then slid into place in the housing, the top of the housing having grooves for laterally positioning the plate 33.

Each switch block has at one side a coin ledge 34 which serves to space this coin block from the next adjacent block and to provide a passage 35 for coins. In Fig. 4 the coin block is set for the smallest sized coin. In order to set it for the next size coin, the switch block together with the coin box and the wedge plate are removed and that particular switch block is reset into one of the sets of positioning grooves which will place that particular coin block at the desired distance from the front to provide a passage 35 of the desired width to accommodate the particular coin which it is desired shall be used.

20 At the same time the width of the coin slot 27 is similarly regulated, as shown in Fig. 2. This is done by providing at the back of the slot 27 in the coin plate 36 a series of circular recesses 37 in any one of which may be placed 25 a small button 38. Thus the button if placed in the center opening, as shown in the right-hand slot of Fig. 2, will effectually close this slot so that no coin can be inserted. By placing it in the other openings, however, or by omitting it 30 entirely, the width of the slot is regulated for coins of different diameters.

Back of the series of coin slots 37 lies a slot closing bar 39 (Figs. 8, 9 and 10) which is slidably mounted on pins 40, 41, and having a series 35 of notches 39^a corresponding to the coin slots 27, so that when the slot closing bar is shifted to the left in the full line position shown in Fig. 9, these notches will correspond to the coin slots, thereby enabling the desired coins to be inserted. 40 When, however, this bar is shifted to the right to the dotted line positioning of Fig. 9, these coin slots will be closed. The mechanism for shifting the bar 39 will now be described.

45 Levers 43 and 44 are hingedly mounted on a pin 45. The lever 43 carries a pin 50 which passes loosely through a slot 49 in the bar 39, and has a tension spring 51 connecting it with the bar. As the lever 43 is drawn to the dotted line position (Fig. 9) the spring 51 is tensioned, thereby drawing the bar 39 to the dotted line position against the action of the spring 47. On the lever 43 being returned to the full line position, the spring 47 draws the bar back to the full line position against the pin 40. The lever 44 is connected to the bar 39 through a spring 48 which tends to retract the lever, but the bar 39 is prevented from moving by the pin 50. The lower ends 43^a and 44^a of the levers 43 and 44 respectively, extend into slots 42^c and 42^d respectively, as shown in Figs. 5, 6, and 8.

60 The clock mechanism is shown in front elevation in Fig. 8 and comprises a framework 52 and a main spring 53 which is wound by means of a stem 54 having a squared end which is adapted to receive a key 55 (Fig. 11). The stem 54 carries a pinion 56 which meshes with a gear 57 which is mounted on a shaft (not shown) and which is driven by the clock mechanism at a very slow rate, so that it takes several days 70 for this gear to make a single revolution. A dial 58 graduated to correspond to days and quarters of days is operably carried by this gear and shows through an opening 59 in the front of the housing, as shown in Fig. 1. A pointer 60 indicates the position of this dial. The gear 57

also carries an annular disk 61 having an opening 62. A roller 63 carried by the lever 44 rides upon the outer periphery of this annular disk, as shown in full lines in Fig. 10, but this roller drops into the opening 62 when the dial 58 is 5 in the zero position, as shown in Fig. 8, thereby permitting the lever 44 to move into the dotted line position of Fig. 10. This disk is provided with a series of tapped openings 64, each corresponding to a definite interval of time, say a 10 quarter day on the dial 58. A pin 65 having a threaded end is adapted to be screwed into one of these openings. When so inserted this pin encounters a stop 66 on the inside of the lever 44, as shown in Fig. 10, thereby limiting the 15 amount to which the gear 57 and dial 58 can be wound.

When the clock mechanism, which is of a self-starting type, has thus been wound and started, it will run until the annular disk turns to the 20 point where the opening 62 lies in front of the roller 63 whereupon the spring 46 will shift the lever 44 inwardly and force the roller inward, shifting the slot closing bar to the dotted line position of Fig. 9 wherein the coin slots are 25 closed, and shifting the coin retaining bar 42 to the position shown in Figs. 5 and 15 wherein the slots 42^b coincide with the coin slots, thereby dropping the coins into the coin box below.

In inserting coins care must be taken to wind 30 the clock fully and to remove the key, otherwise the coin cannot be inserted because of the bar 39. If the key is inserted while the dial is in any position other than the zero position, that is while coins are in the slots in the position shown in 35 Fig. 14, the retaining bar will be moved to the position shown in Fig. 15 and all coins will drop into the coin box and the electrical circuits broken thus prematurely terminating the service.

40 Referring now to Figs. 9, 10, and 11, the key 55 is inserted through an opening 67 in the front of the housing 20 and as it passes inwardly it encounters the sloping surface 68 of the lever 43 and the sloping surface 69 of the lever 44, separating 45 the same and moving the lever 43 from the full line position to the dotted line position of Fig. 9, at the same time moving the lever 44 of Fig. 10 to the full line position. If the clock dial is in the zero position before insertion of the key, the lever 44 will be in the dotted line position 50 of Fig. 10 in which the roller 63 lies within the opening 62, as shown in Fig. 8. Insertion of the key therein moves the roller 63 out through the opening 62, so that the gear 57 can be turned to wind up the clock. The number of days or fractions thereof to which the clock mechanism can be wound is fixed by the position of the pin 65 which, as shown in Fig. 8, is four full days, that is sixteen multiples of one-fourth day each.

55 The retaining bar 42 is also controlled by the movements of the levers 43 and 44 acting through the extensions 43^a and 44^a in the slots 42^c and 42^d, respectively, in the bar 42 (Figs. 5 and 6), and serves to control the coin within the slot. A plunger 70 is slideable back and forth through 60 an opening 71 in the front of the housing, and carries a plate 72 having a series of upwardly projecting fingers 73, each of which lies between vertical guides 74 which serve to form vertical slots for the passage of the coin. The plate 72 70 also carries horizontally extending projections 75 which are separated, however, to form passages 76 in line one with each coin slot. The plate 72 is normally held in the retracted position shown in Fig. 6 by means of two springs 77. 75

The plunger 70 may be moved inwardly, as shown in Fig. 5, to force the coins to the position to actuate the switch mechanism, as will presently be described.

5 An electric switch 78 is carried in a suitable opening 79 in each of the switch blocks, the internal mechanism of the switch being shown in Fig. 7. This switch consists of a hollow shell 80 of a suitable hard insulating material having 10 electric leads 81, 82, secured thereto by means of rivets 83, 84, respectively. A switch arm 85 is mounted to oscillate about a pin 86, and carries a metal button 87 which in the position shown in Fig. 7 is out of contact with both the head of the 15 rivet 83 and the spring arm 84^a carried by the rivet 84. When, however, the arm 85 is moved to the right, the button 87 will make electric connection between the head of the rivet 83 and the spring 84^a. A switch lever 88 is secured to a 20 switch operating member 89 which is rotatable upon the pin 86. A spring 90 operably connects the member 89 with the arm 85 so that as the lever 88 moves back and forth past the center, the spring 90 will snap the arm 85 from open position to closed position, or vice versa. The 25 switch lever 88, as shown in Fig. 4, has a spring 91 which normally holds the lever in the position of Fig. 7 wherein the switch is open. The spring 91 is sufficiently strong to overcome the 30 action of the spring 90.

When an appropriate coin A (Figs. 3 and 12) is inserted through one of the coin slots 27, it falls through the passage guided by the ledge 34, through the position A' to the position A², 35 in which it rests on the retaining bar 42 as in Fig. 3, or it may rest on the switch lever 88, as in Fig. 12. After an appropriate coin has been inserted in each of the coin slots, the operator then pushes the plunger 70 thereby forcing the 40 coin from the position A² through to position A³ (Fig. 13) to the position A⁴ (Fig. 14) in which position it is held between the lower end of the switch lever 88, the edge 42^a of the retaining bar, and a pin 92 on the side of the switch block. 45 When the plunger is withdrawn the coin is held in place under tension of the spring 91. Too small a coin, if inserted, will not operate the switch or may drop into the coin box.

It will be understood that before inserting the 50 coins, the operator has first fully wound the clock mechanism until it is stopped by means of the pin 65 which represents the time contracted for. In other words, the pin 65 is set for the particular time contracted for, whether one day or 55 any other predetermined number of days, and the buttons 38 are then placed in the coin slots 27 (Fig. 2) in the appropriate positions to admit of the insertion of coins corresponding to the time contracted for. At the same time the agent 60 sets each coin block in the notches 29, 30, 31 and 32 (Fig. 4) to correspond to the appropriate distance to provide a coin slot of the proper width to accommodate the coin to be inserted therein. Thus the coin slots illustrated in Figs. 1 and 2 65 show the first coin slot at the left of Fig. 1 closed, so that no coin can be inserted. The second slot indicates a nickel, the third a quarter, and the fourth slot a nickel. To operate this device it therefore becomes necessary that a nickel be placed in the second and fourth coin slots, and that a quarter be placed in the third coin slot in order that the device may be operated, since the switches controlled by coins in the second, third and fourth coin slots may be placed in 70 series, under one condition of operation, as will

later be described in connection with the wiring diagram of Fig. 16.

Having inserted all of the coins the user then pushes the plunger 70, thereby placing all the coins in the position of the coin A⁴ (Fig. 14) 5 wherein each coin holds its switch lever 88 in a position wherein its switch is closed. Referring now to Fig. 16, if it is intended that the user shall be entitled to radio reception from a service or wire as X only, the switches 78^a and 78^b, each 10 of which is controlled by a coin, may be wired in series as shown, a hand-operated switch 93 serving to turn on the radio receiver or loud speaker at will. A wire 94 then connects these 15 switches with a suitable loud speaker or radio receiver 95 as the case may be, and thence to ground, or to return wire through a lead 96. While the coin controlled meter here shown has particular application for use in connection with the sale or lease of a radio receiver or loud 20 speaker, it will be understood that it can be used also for the sale or lease on a time basis of various other services, such as refrigerators, telephones, electric signs, and the like.

Numerous arrangements may be made of the 25 switches and of the coin slots for the coin controlling each switch, the one shown in Fig. 16 being illustrative only. Thus, let us assume that there are two radio services, one coming in on the wire X and the other on the wire Y, and the 30 user has the use of the wire X which is obligatory a weekly fee of say a quarter and a nickel, and in addition has the option of taking the other service Y for an additional fee of a nickel. 35 One of the nickel switches and the quarter switch are wired in series with the center post of the double throw switch 93 so that the user can be connected to the wire X. The wire Y, however, is not connected unless he also places a nickel in the other nickel slot. In that case he can 40 have either the X or the Y program by moving the hand-operated switch 93.

Each coin slot may be designed to take several 45 sizes of coins, Figs. 1 and 2, for example, being designated to take a dime, a nickel, and a quarter. These can be combined to cover a great number of coin combinations ranging all the way from a nickel to several dollars, while the clock can automatically deliver a service from six hours to seven days by quarter day intervals. 50 A very flexible servicing device for use in selling or licensing apparatus of this character is thus provided.

I claim:

1. A coin-actuated time-controlled device comprising a clock mechanism, a coin-retaining member movable to an operative and an inoperative position under control of the clock mechanism, and a coin-ejecting element adapted to be held in an operative position by a coin 60 supported by the retaining member when the latter is in operative position and to eject the coin when the retaining member is in its inoperative position.

2. A coin-actuated time-controlled device comprising a clock mechanism, coin-controlled apparatus including a coin slot for each coin of a number of coins, a coin retaining member located adjacent each slot and movable to operative or inoperative position under control of 70 the clock mechanism, an independently movable element for each slot adapted to be held in a certain position by a coin held in a predetermined position by the coin retaining member in the operative position and released in the inop- 75

- erative position of the coin retaining member, means connecting said elements for series operation and a coin box to hold the coins released.
3. A coin-actuated time-controlled electric switching device comprising a clock mechanism, coin controlled apparatus including a coin slot for each coin of a number of coins, a coin retaining member located adjacent each slot and movable to operative or inoperative position under control of the clock mechanism, two or more electric switches connected for series operation and each held closed by a coin held in a predetermined position by the coin retaining member in the operative position and released in the inoperative position of the coin retaining member, and a coin box to hold the coins released.
4. A coin-actuated time-controlled device comprising a clock mechanism, coin-controlled apparatus including a coin slot for each coin of a number of coins, a coin retaining member located in each slot and movable to operative or inoperative position under control of the clock mechanism, an element held in a certain position by a coin supported by the coin retaining member in the operative position and released in the inoperative position of the coin retaining member, a coin box to hold the coins released, and a member controlled by the clock mechanism to close the coin slots when the clock is in zero or inoperative position or by a key for the clock mechanism when the key is inserted.
5. A coin-actuated time-controlled electric switching device comprising a clock mechanism, coin controlled apparatus including a coin slot for each coin of a number of coins, a coin retaining member located in each slot and movable to operative or inoperative position under control of the clock mechanism, one or more electric switches each held closed by a coin held in a predetermined position by the coin retaining member in the operative position and released in the inoperative position of the coin retaining member, a coin box to hold the coins released, and a bar controlled by the clock mechanism to close the coin slots when the clock is in zero or inoperative position or by a key for the clock mechanism when the key is inserted.
6. The switching device according to claim 3, characterized by a switch block having means forming the inner side of each coin slot and having an electric switch contained therein with a switch lever lying in the path of the coin in the slot and having its axis at the inner side of the coin slot so that a proper coin in the coin slot may operate the switch lever, the switch block being adjustable relative to the outer side of the coin slot to provide coin passages of different widths to accommodate coins of different diameters.
7. A coin-actuated time-controlled device comprising a clock mechanism, a coin-retaining member movable to an operative and an inoperative position under control of the clock mechanism, and an element adapted to be held in an operative position by a coin supported by the retaining member when the latter is in operative position and to be released when the retaining member is in its inoperative position, and means for forcing a coin into operative engagement with the element and for retaining the coin in such position under pressure exerted by the element.
8. A coin-actuated time-controlled device comprising a clock mechanism, coin-controlled apparatus including a coin slot for each coin of a number of coins, a slot closing member, a coin retaining member located in each slot and movable to operative or inoperative position under control of the clock mechanism, means for setting said clock mechanism into operation for a predetermined period of time, means operable by said last mentioned means for operating said
- apparatus including a coin slot for each coin of a number of coins, a coin retaining member located in each slot and movable to operative or inoperative position under control of the clock mechanism, an element in each slot adapted to be held in a certain position by coins held in predetermined positions by the coin retaining member in the operative position and released in the inoperative position of the coin retaining member, a coin box to hold the coins released, and means for simultaneously forcing each coin into said predetermined positions on the retaining member and holding said coins under pressure from its switch lever whereby each switch is held closed by a coin.
9. A coin-actuated time-controlled device comprising a clock mechanism, a coin-retaining member movable to an operative and an inoperative position under control of the clock mechanism, means adjustable to a predetermined setting to receive and deliver a coin of required dimension to said retaining member, an element adapted to be held in an operative position by a required coin supported by the retaining member when the latter is in operative position and to be released when the retaining member is in its inoperative position, the clock mechanism having means operable for a given coin setting to limit the maximum time for which the clock mechanism may be wound to run.
10. A coin-actuated time-controlled device comprising a clock mechanism, coin-controlled apparatus including a coin slot for each coin of a number of coins, a coin retaining member located in each slot and movable to operative or inoperative position under control of the clock mechanism, an element held in a certain position by a coin held in a predetermined position by the coin retaining member in the operative position and released in the inoperative position of the coin retaining member, means for adjustably supporting said element for operation by a coin of desired dimension, and a coin box to hold the coins released, the clock mechanism having an adjustable stop for limiting the maximum time for which the clock mechanism may be wound to run for a desired coin setting of said element.
11. A coin-actuated time-controlled device comprising a clock mechanism, a coin-retaining member movable to an operative and an inoperative position under control of the clock mechanism, means for setting said clock mechanism into operation for a predetermined period of time, means operable by said last mentioned means for moving said coin retaining member into inoperative position, whereby the clock setting means cannot be controlled by the user except by moving the coin retaining member to the inoperative position and an element adapted to be held in an operative position by a coin supported by the retaining member when the latter is in operative position and to be released when the retaining member is in its inoperative position.
12. A coin-actuated time-controlled device comprising a clock mechanism, coin-controlled apparatus including a coin slot for each coin of a number of coins, a slot closing member, a coin retaining member located in each slot and movable to operative or inoperative position under control of the clock mechanism, means for setting said clock mechanism into operation for a predetermined period of time, means operable by said last mentioned means for operating said

slot closing means and moving said coin retaining member to inoperative position, whereby the clock setting means cannot be controlled by the user except by moving the coin retaining and slot closing members to inoperative positions, an element held in a certain position by a coin held in a predetermined position by the coin retaining member in the operative position and released in the inoperative position 10 of the coin retaining member, and a coin box to hold the coins released.

13. A coin-actuated time-controlled electric switching device comprising a clock mechanism, a coin controlled apparatus having a plurality 15 of coin slots, a switch block forming one side of each coin slot and having an electric switch contained therein, an independently movable switch lever associated with each slot, means to move coins deposited in each slot into predetermined positions to hold said levers in switch 20 operating position, and a member movable to operative or inoperative position under control of

the clock mechanism and cooperating with each of said levers to retain coins in predetermined positions when said member is in operative position and to release the coins when in inoperative position.

14. A coin-actuated time-controlled electric switching device, comprising a clock mechanism, a coin controlled apparatus having a plurality of coin slots, a removable coin actuated switch block forming one side of each coin slot, means 10 adjustably mounting each switch block relative to the opposite side of its respective slot to accommodate a coin of desired diameter, and a coin-retaining member movable to operative or inoperative position under control of the clock 15 mechanism and cooperating with each of said switch blocks to retain coins in predetermined positions when said member is in operative position and to release the coins when in inoperative position.

20 SAMUEL LEE MILLER.
